COMBINED BOTTLE AND CLOSURE THEREFOR

Robert J. Dunlop, Enoch Square, Glasgow, Scotland, assignor to Wm. Teacher & Sons Limited, Glasgow, Scotland, a corporation of the United Kingdom and Northern Ireland

Filed Sept. 7, 1967, Ser. No. 8,523

Claims priority, application Great Britain Mar. 28, 1967

Term of patent 14 years

U.S. Cl. D9—95

Int. Cl. D9—01

FIG. 3

FIG. 4

FIG. 6

FIG. 2

FIG. 5

FIG. 1

FIG. 1 is an exploded front elevational view of a combined bottle and closure therefor showing my new design, the rear view being the same;

FIG. 2 is a side elevational view with the closure in place, the opposite side being the same;

FIG. 3 is a top plan view;

FIG. 4 is a bottom plan view;

FIG. 5 is a vertical sectional view taken through the center of the closure; and,

FIG. 6 is a sectional view taken on the line 6—6 of FIG. 1.

I claim:

The ornamental design for a combined bottle and closure therefor, substantially as shown and described.
